UNITED STATES PATENT OFFICE.

JAMES MARION CALLAHAN, OF WASHINGTON, DISTRICT OF COLUMBIA.

ARCH-SUPPORT.

1,221,833.

Specification of Letters Patent. Patented Apr. 10, 1917.

Application filed March 20, 1915. Serial No. 15,824.

To all whom it may concern:

Be it known that I, JAMES M. CALLAHAN, a citizen of the United States, residing at the city of Washington, District of Columbia, 5 have invented certain new and useful Improvements in Arch-Supports, of which the following is a specification.

This invention relates to an improvement in instep or arch supports, and the object is 10 to provide means to be inserted with a shoe for supporting the arch of the instep to prevent its breaking down or, if weakened, to sustain the parts in normal position.

A further object is the provision of means 15 for adjusting the elevation of the support throughout its length to cause the support to conform to the foot of the wearer, and to afford a support to the arch at the point where it is most needed.

20 The invention consists of certain novel features of construction and combinations of parts which will be hereinafter described and pointed out in the claims.

In the accompanying drawings:—

25 Figure 1 is a bottom plan view of the invention;

Fig. 2 is a longitudinal vertical sectional view;

30 Fig. 3 is a cross-sectional view through the support; and

Figs. 4 and 5 are detail views in elevation of the fastening means.

A, represents the main plate of the support, which is arched lengthwise. An auxiliary plate 2 is connected to the plate A by 35 means of rivets 3. The plate 2 has one edge thereof curved upwardly to conform to the curvature of the normal foot.

An insole or leather covering 4, is mounted 40 upon the plates, which conform in shape thereto, and it is connected to the plates by means of rivets 5. The insole or covering 4, gradually diminishes in thickness to nothing at its end as shown at 6, 6.

45 Interposed between the covering 4 and the auxiliary plate 2 is a removable pad 7, preferably of rubber, and this pad 7 is provided with the studs 8 and 9. The stud 8 is provided with a cross-head 10.

50 The auxiliary plate 2 is provided at each longitudinal edge with a row of oblong or oval slots 11, and the plate A is provided with a row of oblong or oval slots 12 along one edge conforming to the slots 11 of the 55 plate 2, and on the other edge with a row of

circular openings 13. The cross-head 10 of the stud 8 is adapted to be inserted through one of the slots 11 and then through one of the circular openings in the plate A. The pad 7 is then given a quarter turn causing 60 the cross-head to cross the slot and engage the plate 2 for fastening the pad thereto. The stud 9 is then inserted through the slots 11 and 12 of the plates 2 and A for holding the pad against movement.

65 By inserting the studs through the slots of the plates 2 and A the pad can be fastened to the plates, and moved longitudinally of the plates to bring the pad to the proper position to afford support to the instep or 70 arch where most needed.

These pads can be made of various thicknesses to accommodate various conditions of arches. Some arches require a very thin pad to produce the desired elevation, while others would require a much larger pad. 75 The provision for the adjustment of the pad, will however, overcome to a marked degree the necessity for the use of pads of varying thicknesses, because by locating and fastening the pad to the plates at one of the several places provided for such fastening it will often afford the desired support for the arch, and at the same time support that part of the arch which is the weakest, and which 80 can not be supported by the arch generally used.

85 The plate A, is preferably provided with a hole 14 at the heel to receive a screw 16 when desired, and fasten it to the shoe 15. In 90 many instances this will not be necessary or desired.

95 It is evident that many slight changes may be made in the form and arrangement of the various parts described without departing from the spirit and scope of my invention, and hence I do not wish to be limited to the exact construction herein set forth as for instance, the elevation or arch of the support can be changed to suit the demands, as the 100 metal is such that it can be bent to change the arch.

I claim:—

1. In an arch support, the combination with a covering and a metal plate connected together at one end, of a pad interposed between the plate and covering and capable of longitudinal movement, said plate and covering being disconnected at their other terminal to permit of the insertion of the pad 110

therebetween, and means for holding the pad in its different longitudinally adjusted positions.

2. In an arch support, the combination with a covering and a slotted metal plate connected together at one end, of a pad interposed between the plate and covering and capable of longitudinal movement, said plate and covering being disconnected at their other terminal to permit of the insertion of the pad therebetween, and means carried by the pad adapted to be inserted through the slots in the plate for fastening the pad to the plate.
- 15 3. An arch support comprising a main plate arched lengthwise, an auxiliary plate secured thereto, said plates being slotted, and a pad provided with studs adapted to enter the slots in said plates, one of the studs, capable of being turned in the slots to fasten the pad to one of said plates.
- 20 4. An arch support comprising a main plate, an auxiliary plate, an insole or covering secured to one of said plates with one end

of the insole or covering free or disconnected, and a pad inserted between one of said plates and the insole or covering and detachably fastened to one of said plates.

- 25 5. In an arch support, the combination with a covering and a plate, said plate provided with rows of openings, of a pad interposed between the plate and covering, and studs connected to the pad, one of the studs provided with a cross-head, said last mentioned stud adapted to be inserted in an opening in the plate, and the pad given a quarter turn for causing the cross-head of the stud to engage the plate for fastening the plate and pad together, and the other stud adapted to enter an opening of another row 30 of openings for holding the pad against lateral movement.

35 In testimony whereof I affix my signature, in the presence of two witnesses.

JAMES MARION CALLAHAN.
